UNITED STATES PATENT OFFICE.

CLARA ELSENE WILLIAMS, OF NEW YORK, N. Y.

DESIGN FOR A LAMP-SHADE.

58,124.

Specification for Design.

Patented June 7, 1921.

Application filed October 25, 1920. Serial No. 419,547. Term of patent 14 years.

To all whom it may concern:

Be it known that I, CLARA ELSENE WILLIAMS, a citizen of the United States, residing at New York city, in the county and State of New York, have invented a new, original and ornamental Design for a Lamp-Shade, of which the following is a specification, reference being had to the accompanying drawings, forming part thereof.

Drawing.

The drawing is a view of the lamp shade in its flattened form.

Description.

The flattened form shown in the drawing is constructed from translucent material, and the ends are drawn together and attached in service.

I claim:

The ornamental design for a lamp shade, as shown.
